ATTORNEY

UNITED STATES PATENT OFFICE.

AUGUST DISK, OF LOGANVILLE, WISCONSIN.

DRAINING DEVICE.

1,426,262.

Specification of Letters Patent. Patented Aug. 15, 1922.

Application filed September 1, 1921. Serial No. 497,607.

To all whom it may concern:

Be it known that I, AUGUST DISK, a citizen of the United States, residing at Loganville, in the county of Sauk and State of Wisconsin, have invented new and useful Improvements in Draining Devices, of which the following is a specification.

My present invention pertains to the drainage of lands and the like, and it contemplates the provision of a machine through the medium of which the land may be readily and cheaply drained and this without the necessity of laying pipe for conducting water and the like away from the land.

The invention further contemplates a machine for use in connection with the drainage of lands that is not only inexpensive to produce and maintain but is likewise simple in operation and requires the attention of but one person.

The invention in all of its details will be fully understood from the following description and claim, when the same are read in connection with the drawings, accompanying and forming part of this specification, in which:

Figure 1 is a side elevation of my novel draining machine.

Figure 2 is a top plan view of the machine, and,

Figure 3 is a detailed sectional view of the main beam and the device I employ to remove the dirt to permit free flow of drainage.

The invention as set forth in the drawings and specification will be fully understood from the following description and in said description similar numerals designate corresponding parts in all of the views of the drawings.

My novel land draining machinery comprises the main beam 1 that extends approximately the full length of the machine and at a point slightly adjacent the center thereof, I provide the brace rod formed of iron or suitable material and provided with the cutting edge 2^a as illustrated.

Secured to the beam 1 at an angle thereto at its upper end is a cross rod of iron or similar material and the said rod 3 is pivotally secured at its lower end to the lower end of the rod 2. It will also be seen that the dirt removing portion 4 is secured to the lower end of the rod 2 through the medium of the pin illustrated clearly in Figure 3.

This dirt removing or forcing portion 4 comprises the most important feature of my invention and by preference is formed of iron or pipe and is solid in construction. It is closed at its ends and on one end it is blunt and at its opposite end it is pointed whereby it will plow through the ground during operation of the machine. I would distinctly have it understood that the rod or pipe 4 may be of any diameter compatible with its purpose.

Mounted on the upper end of the beam 1 is a rack 8 and secured to the upper end of the rod 5 is a lever 6 having the handle 7 and this handle may be moved forwardly and backwardly to raise and lower the rod 5 and consequently the pipe or dirt removing element 4. Manifestly when the pawl of the lever or handle 7 is released from the teeth of the rack 8, the lever may be moved in either forward or rearward motion as is desirable when the operator wishes to point the pipe or dirt remover upwardly or downwardly.

At its opposite end from the rods 2 and 5, the machine is provided with the traction wheels 11, preferably two in number, and the said wheels are secured to the axle shown which is bent as indicated by 12 and the beam 1 is secured to the bent portion of the said axle.

Permanently secured to the rod 2 is the draw bar 13, and extending from the outer end of the draw bar 13 to the free or outer end of the beam 1 is a chain 14.

As shown in Figures 1 and 2, I provide the circular disk having the outer cutting edge and the beam 1 is supported on the axle of the disk as shown.

In the practical operation of the machinery, the dirt removing or forcing element 4 is pushed into the ground to the depth desired, and power is applied to the draw bar. This will force the pointed end of the portion 4 through the ground, and dirt will be pushed forwardly and to the sides and around opening made in the ground. When occasion demands the portion 4 may be square, but it is the purpose of this invention to eliminate the necessity of digging a trench and then laying pipe. With my novel machine, the dirt will be forced to one side and a perfectly open space produced beneath the ground in such a manner that it will remain in said position for many years.

The device as before stated may be raised

or lowered by simple manipulation of the lever 6, and during the operation of the invention, the colter or disk 10 as well as the cutting edge of the rod 2 will materially assist in the ready forward movement of the machine through the ground.

I would distinctly have it understood that in the future practice of the invention, such changes or modifications may be made 10 as fairly fall within the scope of my appended claim.

Having described my invention, what I claim and desire to secure by Letters-Patent is:

15 In means for the purpose set forth, the combination of a main beam, a small disk wheel secured at a point slightly beyond the transverse center of the beam, traction wheels secured upon the beam in front of 20 the disk wheel, downwardly extending brace

rods depending from the main beam, angle brace rods secured to the first named brace rods and at an angle on the main beam, guide rods secured to the main beam, a movable brace rod arranged adjacent the main beam, an arm secured to the movable rod, 25 a rack mounted on the main beam and adapted to act as a fulcrum for the arm, a dirt removing log having a pointed end secured to the brace rods and movable rod, and a draw bar mounted on the upper end of certain of the brace rods.

In testimony whereof I have hereunto set my hand in presence of two subscribing witnesses.

AUGUST DISK.
